ADJUSTABLE PICTURE FRAME

Maxwell Mandell and Benjamin Schwartz,
New York, N. Y.

Application September 10, 1936, Serial No. 100,063

4 Claims. (Cl. 40—155)

This invention relates to adjustable frames or supports for pictures, placards, mirrors and the like, and has for its object the provision of a device of the character described which is simple in construction and which is readily adjustable to accommodate pictures, etc., of varying sizes and conformations.

In the preferred form of invention, the frame is so constituted and constructed that the same may be folded or "collapsed" or nested into relatively small compass, with the advantages accruing therefrom, and yet without separating or dismantling any of the elements of said frame. Conversely, while the adjustable frame or support is arranged to be packaged, preferably, in the "collapsed" or nested form, nevertheless, it is so constituted and constructed that it may readily and easily be manipulated into position to receive the picture, placard, mirror or the like which it is desired to frame or support.

Preferably, the invention comprises a plurality of arms, when in operative use, radiating or extending from, and held together at or adjacent their inner extremities by a common locking element. Said arms are adapted to be extensible and rotatable relative to the locking element so as to accommodate, support or receive a picture, placard, mirror or the like of varying sizes and conformations.

Preferably, the said arms are provided with a medial, longitudinal slot in the body thereof, a screw or such lock element being passed through the slots of said arms, so that the latter may be translationally adjusted as well as rotated, with the screw or equivalent element acting as guide and a pivot.

The outer extremities of said arms are provided with means for engaging a portion or section of the object to be framed or supported, said means being preferably swivelably attached to the outer extremities of said arms.

From the nature of the construction of the invention, it will be seen that the units or arms may, when not in operative use, be stacked or superimposed one upon the other to compact the same.

Keeping these factors in mind, it will be seen where the accompanying drawings bear out the features of invention above described, generally, as well as in detail, including modified forms falling within the scope of this invention.

In the drawings:

Fig. 1 is a plan view of our frame in the so-called "nested" condition, while Fig. 2 shows the same "fanned" out or unfolded, ready to receive a picture, placard or the like.

Fig. 3 is a side view of Fig. 2, partly in section.

Fig. 4 is a flat strip of metal, longitudinally slotted composing one of the elements of our frame.

Fig. 5 is a plan view of one of the arms of the frame showing a modified form, and Fig. 5A is a sectional view taken on line 5A—5A of Fig. 5.

Fig. 6 is a plan view of a modification of the frame arm associated with arm shown in Fig. 5, and Fig. 6A is a sectional view taken along line 6A—6A on Fig. 6.

Fig. 7 is a plan view showing a frame embodying members of the type shown in Figs. 5 and 6, while Fig. 8 is a sectional view on line 8—8 of Fig. 7.

Fig. 9 is a partial perspective view of telescoping slotted tubular or channeled metal frame members showing a modified form of the complementary or telescoping members of Figs. 5 and 6.

Fig. 10 is a detail of a corner or end-channelled member of a form suitable to be used in conjunction with circular mirrors or the like, the former having a part or extension for hiding the hiatus between the circular mirror and the like, and the said corner or end member.

Figs. 11 and 12 are partial plan views showing modified forms of arms and attaching means.

Fig. 13 is a plan view of our invention as applied to a picture.

Referring now to the said drawings it will be seen that the invention comprises the provision of a plurality of medially slotted members or arms having a common pivot 1 with respect to which said members or arms are rotationally as well as translationally or extensibly adjustable.

In Figs. 1 to 4 inclusive, the frame is shown as comprising four arms or members 2, each member consisting of a longitudinally slotted flat metal stamping 3, to the extremities of which are relatively loosely riveted at 4, for swivable movement, channeled corner members 5, arranged to engage, receive, or accommodate an edge or section of a picture with its mat, glass and backing, or a placard, mirror or the like (see generally 6, Fig. 3).

It will be observed that in the case of Figs. 1 to 4 inclusive, each arm or member 2 is individually and separately movable or adjustable both longitudinally or extensibly and rotationally so that the said members or arms 2, may be "fanned" out to a greater degree of symmetry or asymmetry than in the case of the telescoping members or arms of Figs. 5 to 9 inclusive, because the telescoping complementary members are not rotationally movable with respect to each other, though the two pairs of telescoping, complementary arms or members, as clearly shown in Fig. 7, are rotationally movable or adjustable with respect to each other.

The said pivot or connecting means 1 may be an ordinary screw passing through the slot of each arm or member of the frame, and secured to said pivot or screw, may be a supporting leg or

easel 7, consisting, preferably, of a longitudinally slotted strip of metal, the said screw passing through the longitudinal slot of said leg. A wing nut 8 may be employed on the screw 1 to lock together the arms or members 2, and the leg 7 (where the latter is used).

Where it is the purpose to hang the said frame, use is made of perforated ears 9, secured to the channeled corner members 5, by the rivets 4, as clearly indicated in Fig. 3.

In the modification shown in Figs. 5 to 8 inclusive, it will be observed that the arms are of somewhat different construction from that shown in Figs. 1 to 4. Here the arms are complementary and telescoping, and the complementary arms, as above stated, are longitudinally movable with respect to each other and not rotationally. Fig. 5 shows one of the complementary arms 10 slotted longitudinally as in the first named instance, but being provided with longitudinal side ledges or tongues 11, as more clearly illustrated by the sectional view in Fig. 5A.

Fig. 6 shows the complementary arm 12 to arm 10 of Fig. 5. In Fig. 6 the arm is longitudinally slotted and provided with a groove or channel 13 in the side portions thereof to accommodate the ledges or tongues 11, 11 of Fig. 5.

Fig. 9 is a still further modification of the arm construction of the frame. Here, as in Figs. 5 to 8 inclusive, the arms are telescoping but both arms in this instance consist of channeled or tubular members 14 and 15 respectively, the one telescoping with the other. Here, as in the case of the construction of Figs. 5 to 8 inclusive, the arms are paired, complementary and telescoping and the individuals of a pair have only translational or longitudinal movement with respect to its complement.

Where circular mirrors 16 (Fig. 10) or other curved objects are to be supported in the frame, there may be provided channeled corners 5, 5, with an extended portion or piece 17 to cover the hiatus between the periphery of the mirror or other circular object and the said corner members 5.

In the modification illustrated in Fig. 11 the arms 12 are slidably pivoted to a disc 20, the disc being provided with slots 21 and the inner extremities of the arms 12' are provided with a hole 45 through which extends a clamp screw 22, the screw extending also through the slot 21. This arrangement allows for free sliding within limits of the arms along the respective disc slots for longitudinal adjustment of the corner brackets 55 or pieces 5' and also permits of any necessary pivotal adjustment of the arms with respect to the disc to accommodate the corner pieces 5 to the configuration of the picture, mirror, placard or the like which is to be framed.

Fig. 12 is illustrative of still another embodiment of the invention in which the arms 5'' are each made up of two telescopic members 23 and 24 with a clamp screw 25 for locking the two members together in adjustable position. In this embodiment one of the members 24 of each arm is pivotally connected to a disc 26. The free extremity of the other member 23 of each arm has pivoted to it the corner piece 5'.

Although we have described our improvements with considerable detail and with respect to certain particular forms of our invention, we do not desire to be limited to such details since many changes and modifications in the form, arrange-

ments, proportions, and sizes thereof, may well be made without departing from the spirit and scope of our invention in its broadest aspect.

Having thus described our invention, what we claim as new and desire to secure by Letters Patent, is:

1. An adjustable frame comprising a plurality of pairs of extensible arms, one arm of each pair having a closed-ended longitudinal slot extending substantially its entire length, and having its outer longitudinal side edges provided with a reduced tongue, the other arm of each pair being bifurcated substantially throughout its length, the interior longitudinal edges of the resulting prongs having a grooved channel to slidably accommodate the reduced tongues if the first arm, each of said arms having at its free extremity, pivoted means for holding a section of an object to be framed, and a common pivotal member passing through all of said slots and bifurcations, around which member said pairs of arms may be moved rotationally.

2. An adjustable frame comprising a plurality of pairs of extensible arms, one arm of each pair having a closed-ended longitudinal slot extending substantially its entire length, and having its outer longitudinal side edges provided with a reduced tongue, the other arm of each pair being bifurcated substantially throughout its length, the interior longitudinal edges of the resulting prongs having a grooved channel to slidably accommodate the reduced tongues if the first arm, each of said arms having at its free extremity, pivoted means for holding a section of an object to be framed, and a common pivotal member passing through all of said slots and bifurcations, around which member said pairs of arms may be moved rotationally.

3. An adjustable frame comprising a plurality of pairs of extensible arms, one arm of each pair having a closed-ended longitudinal slot extending substantially its entire length, the other arm of each pair being bifurcated substantially throughout its length, the interior longitudinal edges of the resulting prongs having a grooved channel to slidably accommodate the edges of the first arm, each of said arms having at its free extremity, pivoted means for holding a section of an object to be framed, and a common pivotal member passing through all of said slots and bifurcations, around which member said pairs of arms may be moved rotationally.

4. An adjustable frame comprising a plurality of pairs of extensible arms, one arm of each pair having a closed-ended longitudinal slot extending substantially its entire length, the other arm of each pair being bifurcated substantially throughout its length, the interior longitudinal edges of the resulting prongs having a grooved channel to slidably accommodate the edges of the first arm, each of said arms having at its free extremity, pivoted means for holding a section of an object to be framed, and a common pivotal member passing through all of said slots and bifurcations, around which member said pairs of arms may be moved rotationally.

MAXWELL MANDELL.
BENJAMIN SCHWARTZ.
